NELSON M. BAKER, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

GRINDSTONE HONING DEVICE.

Application filed August 6, 1923. Serial No. 656,009.

This invention relates to an improved grind-stone honing device, and has particular reference to a hone adapted for use on a bevel edging machine employing a 5 V-shaped stone, although the invention may be used in conjunction with any type of grind-stone, or the like.

The process of sizing and of beveling of lenses is necessarily a delicate and painstaking one, and requires that the lenses be 10 held between suitable clamping heads by friction alone, and the pressure of contact of the lenses with the grind-stone must, therefore, be light and substantially uniform to prevent displacement of the lenses with reference to their clamping heads. It 15 will be seen that this requirement necessitates having a stone, the faces of which are absolutely free from grooves, or the like.

20 A very important object of this invention is to provide a honing device to be used in conjunction with a grind-stone that will positively prevent the forming of grooves in the stone, and which may be made to contact with the grinding faces of the stone at 25 all times, but if it is desired the honing portions may be moved away from the stone.

Another very important object of the invention is to provide a honing device that 30 is especially well adapted for use on a V-shaped stone, and to this end a hone is provided for each face thereof, and means are associated therewith whereby both hones may be adjusted to and from the stone 35 simultaneously so that the same honing effect may be had on both grinding faces of the stone, for obvious reasons.

Another important feature of the invention 40 is that of having the hones reciprocated across the entire face of the stone, so that the entire face will be smooth, as well as making the apex of the stone constant.

A still further object of the invention is to provide a honing device of this character 45 which is exceptionally strong, durable, comparatively inexpensive in construction, and which is particularly well adapted to the uses for which it is designed.

Other important objects of the invention 50 will become apparent during the course of the following description.

In the drawings, wherein like numerals

are employed to designate like parts throughout the same:

Figure 1 is a top plan view of my invention, 55

Figure 2 is a section taken on line 2—2.

Figure 3 is a fragmentary detail of a modification thereof.

Figure 4 is a section taken substantially 60 on line 4—4 of Figure 3 and looking in the direction of the arrow.

Figure 5 is a top plan view of the invention showing the means for simultaneously moving the hone portions to and from 65 the stone, and

Figure 6 is a fragmentary sectional detail thereof.

In the drawings, wherein for the purpose of illustration, is shown the preferred embodiment of the invention, the numeral 10 designates the grinding stone, which is illustrated as a V-shaped stone, being carried on the shaft 11 arranged in suitable bearings 12.

Arranged in proximity to the stone 10 is 75 a housing 13 through which is journaled a shaft 14, which is disposed transversely of the stone and is provided at one end with the sprocket wheel 15, over which is trained a sprocket chain 16 which derives power from 80 the sprocket wheel 17 which is carried by one end of the shaft 11. The housing 13 has a cut out portion immediately in front of the stone, as is clearly illustrated in Figure 1 of the drawings. A worm 18 is keyed 85 to the shaft 14 and meshes with a worm wheel 19 which is carried by a stub shaft 20 journaled in the housing 13, and arranged at right angles to the shaft 14. Near the

opposite end of the stub shaft 20 is keyed 90 a bevelled pinion 21 which meshes respectively with the bevelled pinions 22 and 23.

The pinions 22 and 23, respectively, are mounted on the inner end of the shafts 24 and 25, respectively, which shafts are so disposed as to be arranged parallel to their respective cutting faces of the grinding stone 10. The shafts 24 and 25, of course, pass through suitable sleeves 26 formed integral with the housing 13, as is clearly illustrated in Figure 4 of the drawings. The outer ends 95 of the shafts 24 and 25 are provided with the cams 27. The upper end of the housing 13, that is, the portion disposed above the

shafts, is formed into a dove-tail rib 28. Mounted above the dove-tail ribs 28 are the hone carriages 29 and 30, which carry the honing portions 31. The honing carriages 29 and 30 are carried by the slide portions 32, which are provided on their under side with the dove-tail grooves 33 adapted to receive the dove-tail rib 28. The members 32 also are provided with the arms 34 having the spaced fingers 35, between which the cam 27 is adapted to operate, in which manner the member 32 carrying the hone carriage 29 is reciprocated along the dove-tail rib 28 in such a manner that the honing portion 31 will traverse the entire width of the grinding surface of the stone 10. It will, of course, be seen that the pitch of the cam 27 will be dependent upon the width of the face of the stone and the size of the honing member used.

It will be seen that the power is derived through the medium of the sprocket chain and sprocket wheels, by which means the shaft 14 upon which the worm 18 is keyed will be rotated so as to impart a rotary motion to the shaft 20 by reason of the worm wheel 19 meshing with the worm. In this manner the pinion 21 which is carried by the opposite end of the shaft will impart movement to the pinions 22 and 23, which are carried by the shafts 24 and 25 which have at their opposite ends the cams 27 so that a reciprocatory movement is given to the honing carriages whereby the hones are reciprocated across the faces of the stone 10. Due to the arrangement of the cams 27, as illustrated in Figure 1 of the drawings, the hones 31 will be reciprocated and maintained in the same relative spaced relation at all times during their operation.

It is very essential that hones of the same properties and characteristics be selected for use in honing the faces of the grind-stone, and it is just as important to have means whereby the hones may be adjusted equally in order that both faces of the stone may correspond. To this end I have devised several unique means, one of which is shown in Figure 3 of the drawings. In this form an arm 36 is formed integral with the carriage 32. The hone carriage 29 is provided with a threaded opening running throughout the entire length, directly below the hone 31 and is adapted to receive the threaded end 55 of the shaft 37 which is embraced on either side by the forked ends of the arm 36, and has on its outer end the operating wheel 38, by which means the hone carriage may be moved to and from the stone. Of course, 60 thumb nuts 40 are used to hold the hone 31 within the hone carriage 29.

In Figure 5 of the drawings is shown a modification by which means the hones are adjusted simultaneously. As can be seen, the 65 same structure is used as in the modification

above described, except for the fact that a bevelled pinion or gear 41 is mounted on the outer end of the shaft 38 instead of the hand wheel 39. Brackets 42 support the shafts 43, which shafts are arranged substantially parallel to the shaft 24 and 25, and are provided at their converging ends with the bevelled pinions 44 which mesh as at 45. Of course, the bevelled gears 45 are provided near the opposite ends and are adapted to mesh with the pinions 41. It will, of course, be recognized that the pinions 45 must be allowed to move with the pinions 41 as the carriage 29 reciprocates and to this end the shafts 43 are provided with the elongated slots 46 through which the pins 47 extend, as is shown at 46. The pins 47 are carried by pinions 45, and as the pinions are carried by the brackets 42, as the bracket 42 is moved the pinion will likewise follow. The pinions 45 likewise act as a sliding journal for the shafts 43, as can be seen by an inspection of the drawings.

In order to manipulate this arrangement the hand wheel 48 which carries the pinion 49 is so mounted that the pinion 49 will mesh with one of the pinions 44 and as the pinions 44 mesh, as at 45, the shafts 43 and adjuncts thereto will operate simultaneously so that the hones 31 will be moved to and from the stone simultaneously by a simple operation.

It will thus be seen that I have devised a very simple yet efficient means of maintaining a V-shaped stone in the required condition by means of a very simple honing device which is operated with ease, and which is automatic in its nature as far as the reciprocation of the hones is concerned.

It is to be understood that the form of my invention herewith shown and described is to be taken as the preferred embodiment of the same, and that various changes in the shape, size and arrangement of parts may be resorted to without departing from the spirit of my invention or the scope of the subjoined claims.

Having thus described my invention, what I claim is:

1. In combination with a grinding machine including a rotary stone, a housing arranged in front of the stone, a sleeve carried by the housing, a shaft arranged within the sleeve, a hone carriage associated with the sleeve, a cam carried by the shaft, means to connect said hone carriage and cam, and means to rotate said shaft whereby the hone carriage is reciprocated in the path of the stone face.

2. In combination with a grinding machine including a rotary stone, a shaft journaled in proximity to the stone, means to rotate the shaft, a second shaft geared to the first mentioned shaft, a sleeve for said second shaft, a dove-tail rib carried thereby,

a hone carriage having a dove-tail groove formed therein and adapted to receive the dove-tail rib, and cam means connecting the sleeve and hone carriage whereby the hone carriage is reciprocated by the rotation of the second shaft.

3. In combination with a grinding machine including a rotary stone, a housing arranged in front of the stone, a shaft journaled therethrough and arranged in alignment with the grinding stone, a worm for turning the shaft, a bevelled pinion carried on the shaft, hone carriages reciprocally mounted above said housing and connected 10 to said bevelled pinion, means to reciprocate

the hones on rotation of the shaft and means to simultaneously adjust the hones to and from the stone.

4. In combination with a grinding machine including a rotary stone, a pair of 20 hones, means to reciprocate the hones simultaneously, means to maintain the hones in the same spaced relation at all times, a pair of convergent shafts associated with the hones, and a hone wheel associated with one 25 of said convergent shafts, whereby both hones will be operated simultaneously to and from the stone.

NELSON M. BAKER.
